UNITED STATES PATENT OFFICE.

OSCAR F. FORSBERG, OF YONKERS, NEW YORK, ASSIGNOR TO WESTERN ELECTRIC COMPANY, OF NEW YORK, N. Y., A CORPORATION OF ILLINOIS.

COIN-COLLECTOR.

1,096,500.

Specification of Letters Patent.

Patented May 12, 1914.

Application filed September 20, 1911. Serial No. 650,392.

To all whom it may concern:

Be it known that I, OSCAR F. FORSBERG, citizen of the United States, residing at Yonkers, in the county of Westchester and State of New York, have invented a certain new and useful Improvement in Coin-Collectors, of which the following is a full, clear, concise, and exact description.

This invention relates to coin collecting apparatus for use at a telephone pay station.

The invention is designed for use at a pay station where the deposit of a coin is necessary in order that the substation may be able to signal the central office, and to call for a toll line connection the substation deposits coins as indicated by the central office, the central office subsequently making the proper distribution of the coins, that is, either returning them to the calling party or depositing them in a cash box. The deposit of a coin may be automatically signaled to the central office, each coin transmitting a signal of characteristic significance.

The object of this invention is to provide improved apparatus at the substation under the control of the central office operator to direct a deposited coin or deposited coins into either of two separate paths so that the coins may be either returned to the calling party or deposited out of reach of said party, and to provide means whereby access to the coin box is closed against the unauthorized removal or abstraction of the coins either by the introduction of some instrument from the entrance opening or by the reversal of the position of the coin box.

In accordance with this invention, the coin-directing device comprises a pivoted bottomless retaining element having a separate movable closure for its lower end, and suitable means are provided for laterally displacing the closure in either of two directions to selectively dispose of the deposited coin. Preferably both the retaining element and its closure are independently pivoted, the former upon upwardly extending pivoted arms of the latter. The retaining element may be in the form of a bottomless tubular cell and the closure a pivoted U-shaped member having a concave base, the

cell being pivoted to swing between the arms of said U-shaped member and having its lower end closed by the concave base thereof. A polarized electromagnet may be employed to swing the U-shaped member in either of two directions to selectively dispose of a deposited coin.

Referring to the drawings—Figure 1 is an elevation of that part of a coin collector mechanism which embodies the invention, with the chute in section; Fig. 2 is a plan of the mechanism with the upper part of the chute removed, together with an operating electromagnet (shown in dotted lines in Fig. 1) for controlling the same, this view being along the line 2—2 of Fig. 1; Figs. 3 and 4 are different views of the coin-directing mechanism in one of its alternative operated positions.

In the drawing, the chute 60 has branches 54, 55 extending respectively to a return receptacle 75 and to a coin receptacle. Only the upper part and portions of the side walls 75 52 of the coin receptacle are shown in Fig. 1. The two branch chutes 54, 55 are formed in part by an inverted V-shaped partition 46. Just above the convergence 53 of the branch chutes 54, 55 is located the coin-directing 80 device 33 which may comprise a unitary bottomless retaining element *c* and a bottom or closure 37 therefor; the retaining element in its preferred form is a metallic cell or bucket pivoted above its center of gravity to 85 the upper ends of the arms 39, 40 of the closure 37. The bottom or closure 37 is normally in position to completely close the lower end of the section *c* and acts as a support for the coin or coins. This lower end 90 part 37 is concave and the bottom of the part *c* is convex to correspond with the concavity of the part 37.

An arm 70 controlled by the armature of the polarized magnet *p* carries a toothed segment 71 which meshes with a pinion 45, fixed to the pivotal point of the arm 39, to cause the closure 37 to slide out from under the retaining cell *c* in one direction or the other according to the direction in which the armature *a* of magnet *p* is tilted. This causes the load upon the closure 37 to slide off the base of the closure and fall to one side or the other of the point 53 and into

the chute 54 or the chute 55 constituting the opening into the return coin tray or the coin box respectively.

Gravity devices 50 and 51 are supported 5 pivotally by the arms 39 and 40 of the closure 37, so that they move freely thereon, and these gravity devices at their free terminals make contact with diametrically opposite points of the base of the closure. The 10 function of these gravity devices is to maintain the cell *c* in its normal vertical position against the displacing tendency of the falling coins and also to assist in returning the cell to normal after being operated, and are 15 so weighted and pivoted that while they afford slight resistance to the tilting of the closure 37 and the discharge of the coins due to the operation of the magnet *p*, they afford considerable resistance to the tilting 20 of the cell *c*.

At the entrance to the coin box is a gate *g* pivoted at 56 and held in normal position by the spring 57; its upward movement being limited to prevent the gate from completely closing the entrance to the coin box, thus leaving space for a single coin to slide over the surface of the gate *g* into the coin box; this limit of movement is a short pin 58 in the rear wall. The strength of the 25 spring 57 is such that the weight of more than one coin overcomes it, the gate *g* is deflected and the coins drop through. This gate makes it impossible to introduce an instrument into the coin box for the purpose 30 of withdrawing a coin, and in case the coin collecting apparatus is removed from the wall or support and inverted or tilted coins 35 cannot be thrown out.

The coin or coins having been deposited 40 in the coin-directing device 33, it will be assumed that it is desired to deposit them in the cash drawer of the substation. This cash drawer is shown at *d* and is located immediately below the passageway 55, as seen 45 in Fig. 3. In order, therefore, to discharge the coin now held in the device 33 into the cash drawer, it will only be necessary to rotate the wheel 45 in a clockwise direction. To do this the operator will impress upon 50 the circuit current of such polarity and strength as to energize the polarized magnet *p* to cause the armature *a* to be attracted by the pole piece 74. This will cause the arm 70 to shift or tilt the closure 37 to the 55 left, as shown in Figs. 3 and 4, and since the cell is loosely pivoted on the arms of the closure it will partake of its movement until arrested by the action of gravity, thus facilitating the discharge of the coin into 60 the passageway 55 leading to the cash box *d*. Assuming now that it is desired to return coins held in directing device 33 to the calling party, it is apparent that it will be necessary to rotate the wheel 45 in a counter-clockwise direction. To accomplish this, 65

current of proper polarity and strength will be impressed upon the line to energize the polarized magnet to attract the armature *a* toward pole piece 73 upon the left. This movement of armature *a* will cause the closure 37 and cell *c* to be tilted toward the right, and the deposited coins to be discharged into the passageway 54 from whence they pass into the refund tray 75, accessible to the calling party. 70

I claim:—

1. A coin collector comprising a pivoted coin retaining element, a pivoted closure therefor located beneath the lower end of said element and adapted to be shifted laterally relative thereto, and means for shifting said element and said closure in opposite directions, respectively. 75

2. A coin collector comprising a coin retaining element, a closure therefor, a common pivotal support for said element and said closure whereby both may be rotated about a common axis, and means for rotating said closure and said element in either of two directions to selectively dispose of a deposited coin. 80

3. In a coin collector, in combination, a coin-directing device adapted to support a deposited coin, comprising a pivoted U-shaped member and a bucket pivoted to swing freely between the arms of said U-shaped member and having as a bottom the base of said member, and means for shifting said U-shaped member in either of two directions to selectively discharge a deposited coin. 85

4. In a coin collector, in combination, a coin-directing device adapted to support a deposited coin, comprising a pivoted U-shaped member and a bottomless tubular cell, said cell being pivoted at its upper edges between the arms of said U-shaped member and having as a closure for its lower end the base of said U-shaped member, and means for shifting said U-shaped member in either of two directions to selectively discharge the deposited coin. 90

5. In a coin collector, in combination, a coin-directing device adapted to support a deposited coin, comprising a pivoted U-shaped member and a tubular cell pivoted to swing freely between the arms of said U-shaped member and having as a bottom the base thereof, the pivotal point of the cell being higher than that of the U-shaped member, and means for swinging said U-shaped member from under said cell in either of two directions to selectively discharge a deposited coin. 100

6. In a coin collector, in combination, a coin-directing device adapted to support a deposited coin, comprising a pivoted U-shaped member and a bottomless tubular cell, said member being pivoted at substantially the midpoints of its arms and said 105

cell being pivoted at its upper edges between the upper ends of said arms to swing freely therebetween, the base of said U-shaped member serving as a closure for said cell, and means for shifting said U-shaped member on its pivots in either of two directions to selectively discharge the deposited coin.

In witness whereof, I hereunto subscribe my name this 16th day of September, A. D. 1911.

OSCAR F. FORSBERG.
